UNITED STATES PATENT OFFICE.

THOMAS F. ROONEY, OF ST. LOUIS, MISSOURI, ASSIGNOR, BY DIRECT AND MESNE ASSIGNMENTS, TO UNITED SHOE MACHINERY COMPANY, OF PATERSON, NEW JERSEY, A CORPORATION OF NEW JERSEY.

INSOLE FOR SHOES.

1,140,918.

Specification of Letters Patent. Patented May 25, 1915.

Application filed December 31, 1913. Serial No. 809,599.

To all whom it may concern:

Be it known that I, THOMAS F. ROONEY, a citizen of the United States of America, residing in the city of St. Louis and State of Missouri, have invented certain new and useful Improvements in Insoles for Shoes, of which the following is a specification.

One of the objects of this invention is to facilitate the production of insoles from 10 much lighter material than heretofore.

Another object is to provide an insole with an improved form of channel.

A further object is to provide improved 15 means of forming a channel on insoles whereby much labor is saved.

A still further object is to provide a new and improved means of reinforcement for the channels and lips of insoles.

Other and further objects will appear in 20 the specification, and be specifically pointed out in the appended claims, reference being had to the accompanying drawings exemplifying the invention, and in which,

Figure 1 is a perspective view of the reverse side of an insole showing the groove formed thereon and the lip formed from said groove being upturned. Fig. 2 is a perspective view similar to Fig. 1, showing the channel completely formed on the insole. 30 Fig. 3 is a cross section taken on the line III-III, Fig. 1. Fig. 4 is a cross section taken on the line IV-IV, Fig. 3.

Referring to the drawings: 1 designates the insole for a shoe, said insole having the 35 groove 2 formed therein by a channeling machine. The cutaway portion which is formed from the making of said groove is turned out of said groove thus formed and set up at right angles thereto forming the 40 lip 3. Mounted in said groove is the right angled reinforcing strip 4. Said strip has a horizontal portion 5 and the outstanding portion 6. This strip is cemented in the groove 2 and the outstanding portion 6 is 45 also cemented against the lip 3. Said lip 3

and outstanding portion 6 then form the reinforced channel lip 7.

In some of the present makes of insoles, the material is essentially relatively thick so as to allow a portion of the insole to be 50 cut away to form the channel without making the insole too thin at the cutaway point and so weakening it.

In applicant's improved manner of forming a channel on insoles, the material for the 55 insole can be comparatively thin. Of course, after the groove 2 has been formed in the insole, the insole adjacent the groove will be thin and weak. But the weakened portion of the insole is reinforced by the 60 cementing of the angular strip 4 in the groove; and the outstanding portion 6, which is cemented to the lip 3, will materially strengthen the upturned lip.

What I claim is:

1. An insole having a groove formed 65 therein at a distance from the edge thereof, and a lip formed at right angles to said groove on the inside edge thereof.

2. An insole having a groove formed there- 70 in by cutting along a line at a distance from the edge thereof, a lip formed from the cutaway material of said groove, said lip being turned upwardly from said groove on the inside edge thereof, and an angular reinforcing strip secured in said groove and to said lip.

3. An insole having a groove formed there- 75 in at a distance from the edge thereof, a lip formed at right angles to said groove on the inside edge thereof, and a reinforcing strip secured in said groove, said reinforcing strip adapted to reinforce said lip and the weakened portion of said insole caused by the forming of said groove.

THOMAS F. ROONEY.
